(57) **CLAIM**

I claim the ornamental design for a piercing cap drive socket, as shown and described.

DESCRIPTION

FIG. 1 is a bottom perspective view of a piercing cap drive socket;

FIG. 2 is a bottom planar view of FIG. 1, thereof;

FIG. 3 is a top planar view of FIG. 1, thereof;

FIG. 4 is a front elevation view of FIG. 1, thereof; and,

FIG. 5 is a side elevation view of FIG. 1, thereof.
